UNITED STATES PATENT OFFICE.

HARRY SILVERBERG AND CLARENCE W. BURGER, OF WASHINGTON, DISTRICT OF COLUMBIA, ASSIGNORS OF ONE-FOURTH TO SAID BURGER AND THREE-FOURTHS TO SAID SILVERBERG.

BUTTONHOLE-CUTTING MACHINE.

1,268,398.

Specification of Letters Patent.

Patented June 4, 1918.

Application filed June 15, 1916. Serial No. 103,752.

To all whom it may concern:

Be it known that we, HARRY SILVERBERG and CLARENCE W. BURGER, citizens of the United States, residing at Washington, in the District of Columbia, have invented certain new and useful Improvements in Buttonhole-Cutting Machines, of which the following is a specification.

This invention relates to machines for cutting buttonholes in garments during the process of manufacturing, and is particularly applicable to cutting buttonholes along the front edge of coats.

Heretofore such buttonholes have been cut one at a time by hand, a special punch or cutter being used, and great care on the part of the operator was necessary to insure uniform spacing of the holes, both from each other and from the edge of the garment. The proper locating of the buttonholes by this method consumes a large amount of time and necessitates painstaking measurements and moreover, the results are not always as accurate as might be desired. It is the primary object of the present invention, therefore, to provide a machine having a series of cutters which can be operated simultaneously so as to cut an entire row of holes at a single stroke and to provide means whereby the cutters may be uniformly and accurately set at different distances apart, corresponding with the size and nature of the garment.

A further object is to provide a machine of this character having means for cutting the lapel buttonhole at the same time as the other button holes, and so arranged that the lapel buttonhole may be disposed at any suitable angle required.

Other objects and advantages will appear from the following description, taken in connection with the accompanying drawings which form a part of this specification, and in which:

Figure 1 is a front elevation of the complete machine, parts being in section;

Fig. 2 is a plan view thereof on an enlarged scale;

Fig. 3 is an end elevation of the machine shown in Fig. 1;

Fig. 4 is a detailed perspective view of a gage hereinafter described;

Fig. 5 is a transverse section through the machine as shown in Fig. 1;

Fig. 6 is a transverse section substantially on the line 6—6 of Fig. 2, parts being omitted;

Fig. 7 is a similar view, taken substantially on the line 7—7 of Fig. 2, looking in the direction of the arrow and parts being omitted;

Fig. 8 is a section on the line 8—8 of Fig. 7, looking in the direction of the arrow and parts being omitted;

Fig. 9 is an enlarged side elevation, partly in section, showing one of the cutting blades and method of supporting the same;

Fig. 10 is a front view of the same;

Fig. 11 is a detailed section showing the method of supporting the screw shafts hereinafter described; and

Fig. 12 is a perspective view on an enlarged scale, showing one of the anvils with which the main blades coöperate.

Referring to the drawings in detail, the machine comprises two side frames 1, having widespread feet 2, constituting a base. These side frames are rigidly connected by means of a pair of bars 3, disposed near the top, and a bar 4 near the bottom.

On the bars 3 are mounted a series of cutting devices or mechanisms, designated in their entirety by the reference characters *a, b, c, d, e, f*. The cutting device *e* is fixed, while *a, b, c*, and *d* are independently movable, although connected by a mechanism hereinafter described. The cutting device *f* is movable by means of mechanism wholly independent of that operating the other devices.

Referring to Figs. 5 and 7, one of the cutting devices, such as *b*, is shown in detail. It comprises a body portion 5, having a pair of eyes 6, through which the bars 3 freely pass. At the rear of the body 5 is an upstanding portion 7, carrying at its upper end a pair of spaced eyes 8. Behind the eyes 8 is a horizontally extending lug 9, carrying an adjustable stop pin 10, hereinafter described. The cutter blade is carried by an arm 11, pivoted at 12 between the eyes 8, and provided with a tailpiece 13, co-extensive with the lug 9. A bolt 14 passes downwardly through aligned openings in the tailpiece 13 and lug 9, and carries a light helical spring 15, which presses against the lower side of the lug 9. This spring, as will be

evident, serves to maintain the arm in the position shown in Fig. 5, with the underside of the lug 13 in engagement with the end of the stop pin 10.

- 5 The cutter itself is of the usual form and comprises a blade 16 and heel portion or punch 16^a. The cutter is preferably set into a dove-tailed or T-shaped block 17, which slides into a similarly shaped slot in the end 10 of the arm 11 and is secured in position by means of a set screw 18. An opening 19, extending up through the block and arm 11, permits the escape of punchings cut by the punch 16^a. A suitable stripper comprising 15 a leaf spring 20 is preferably secured to the underside of the arm 11, adjacent the cutter.

These cutters above described coöperate with a rotary anvil 21 (see Fig. 12). This anvil is preferably of hexagonal form, the 20 faces of which are of progressively decreasing lengths, as illustrated at l, m, n, o. The purpose of this is to permit buttonholes of different lengths to be cut, as is well understood in the art. This anvil is provided with 25 a central opening 22, through which a screw 23 passes into the end of the body 5, the anvil being as above intimated rotatable on such screw so that any desired face may be brought into coöperation with the cutter.

- 30 In order to shift the cutting devices a, b, c, d, along the bar 3, as may be required, I preferably provide a screw shaft 24 journaled at one end in the frame 1, as indicated at 27, and provided with a crank 28 by 35 means of which it can be turned.

In shifting the cutting devices, it is, of course, essential that a uniform spacing between such devices be maintained. In other words, while the length of the series, or the 40 distance between the first and last cutting device may be varied, to correspond with coats of different lengths, all of the devices must, of course, remain the same distance apart. In order to produce this peculiar movement, 45 we have devised the mechanism shown more particularly in Fig. 2, which mechanism comprises a lazy tongs structure. This consists of a plurality of links 29, each pair of links being pivoted together at their middle, as indicated at 30, and the pairs of links being 50 pivotedly connected at their ends by means of the pins 31. The center pin 30, at the end of the series, is set into a block 25, which travels upon the screw 24, while one 55 of the intermediate pins 30 carries a supporting block 26, which is not threaded, but rests loosely upon the screw shaft 24. The body 5 of each of the cutting devices a, b, c, d, and e, is provided on its underside with 60 a transverse groove 32, in which groove the ends of the pins 31 of the lazy tongs structure freely slide. As before stated, the cutting device e is fixed. When, therefore, the screw-shaft 24 is rotated, the block 25 travels 65 along the same and expands or contracts

the lazy tongs structure, as the case may be, thus shifting the cutting devices a, b, c, and d, simultaneously. The peculiar thing about the movement, however, is that all of these devices are shifted unequal distances, 70 the amount of travel of each being directly proportional to its distance from the fixed cutting device e. Thus the device a has the greatest movement, b the next, etc. The result of this is that as the series of cutting devices is lengthened or shortened, as the lazy tongs structure is expanded or contracted, the distance between the cutting devices a and b, b and c, c and d, d and e, remains 75 uniform throughout the series. Thus an 80 equal spacing of the buttonholes is assured.

The cutting device f is intended for cutting the lapel buttonhole of a coat, and in order to meet the requirements of this class of work, it is necessary that the cutter be 85 adjustable, both longitudinally and angularly. To this end, the cutter blade 16' is set into a block 38, pivotally secured by a screw 39 to a block 33. This block has a shank 36, which is slidably mounted in an opening in the end of the arm 11 and is secured in adjusted position therein by means of a set screw 37. A stripper 40, similar to the stripper 20, is mounted on the block 33 by means of a pivoted pin 45 in the axis 90 of the screw 39. It will be understood that the blocks 38 and 33 have a swiveled connection so that the block 38 may be turned about the screw 39 to any desired angle. The anvil 41 cooperating with the cutter blade 16', is 95 mounted on a block 42, which is pivotally connected to a block 43 by means of a screw 44. The block 43 has a shank 46, which is slidably mounted in an opening in the body 5 of the cutting device and is secured in adjusted position therein by means of a set screw 47.

The body 5 of the device f is provided with a central downwardly extending lug 35, which has a screw-threaded opening 110 engaging a screw shaft 34 journaled at one end in the frame 1, as indicated at 27, and provided with an operating crank 28.

The two screw shafts 24 and 34 are preferably in alinement, and are together rotatably supported in a lug 6' depending from the body 5 of the cutting device e. As shown in Fig. 11, the shaft 24 has a reduced end 49 which is journaled in the lug 6', while the shaft 34 has a pin 48 which fits 120 into a similarly shaped socket in the end of the shaft 24. Thus, the shafts 24 and 34 are capable of independent movement, each being actuated by its own crank. It will be observed that each of the cutting devices 125 above described comprise a cutter proper and a carrier or carriage which travels along the bars 3, so that the position of the cutters relative to the work may be adjusted as desired.

In order to simultaneously operate all of the cutter arms a common actuator is provided, and a yielding cushion is preferably interposed between such cushion and each 5 individual cutter arm. On top of each arm 11 is mounted a clip 50, held in position by a screw and thumb nut 51, and capable of being swung around such screw when the thumb nut is loosened. The clip 50 is provided 10 with a cup or socket in which is seated a short, stiff helical spring 52, such spring preferably carrying at its upper end a cap 53.

The actuator consists of a beam or bar 54, 15 extending the full length of the machine and disposed directly above the caps 53, which caps are located in a straight line. The bar 54 has trunnions 54' which slide in slotted guideways 55, secured to the end frames 1. Operating rods 56 are secured to the ends of the beam 54 and, extending downwardly adjacent each side frame, are pivotally connected at their lower ends to arms 57 journaled upon the rod 4. The 20 outer end of the arms 57 is connected by a foot-board 58, constituting a treadle. Helical springs 59 are provided and arranged with one end connected to the end frames as at 60, and the other end connected to the 25 rods 56, as indicated at 61. As a result of these springs the treadle 58 and actuating beam 54 are normally held in the elevated position shown in the drawing. When it is desired to operate the cutters, the treadle 30 is depressed, thus drawing the actuating bar down and causing it to engage the caps 53 mounted on the main arms 11. The cutter arms are thus forced downwardly against the anvils, the springs 52 yielding 35 so as to insure each cutter being firmly and operatively pressed against its corresponding anvil.

If, for any reason, it is desired to throw any particular cutter out of action, it is 40 simply necessary to loosen the corresponding thumb nut 51 and swing the clip 50 around to such an extent that the cap 53 and spring 52 are withdrawn from the path of movement of the actuator bar 54. In 45 Fig. 5, the clip is shown in dotted lines as swung to inoperative position.

A suitable work-table is supported by the frames 1 and extends along behind the series of cutters. This table preferably has 50 a thin, forward edge 63, formed of metal or other suitable material, which lies adjacent the anvils 21. Mounted on the edge 63 is a gage, which is shown in detail in Fig. 4. This gage consists of an angle strip 55 64, having near its ends transverse slots 65, through which pass clamping screws, and this strip may be adjusted in accordance with a scale 66 formed on the table and clamped in such a position as will produce 60 the button-holes the desired distance from 65

the edge of the work. The vertical flange of the strip 64 is provided with an extended longitudinal slot 67, through which works a clamping screw 68. This screw 68 passes through one arm 69 of an angle bracket, the 70 other arm 70 of which constitutes a stop against which the end of the garment abuts, so as to properly position the garment under the cutters. This gage is particularly useful in correctly locating the lapel buttonhole. 75

In front of the cutters is provided a shelf or platform 71, supported on brackets 72, secured to the end frames 1. These brackets are provided with slots 73, through which work screws having thumb nuts 74. 80 By this means the shelf 71 can be adjusted vertically to the desired height.

It will thus be seen that we have provided a machine which can be quickly adjusted to accurately cut a series of buttonholes of any desired spacing at a single stroke, and it is thought that the many advantages of our invention will be readily appreciated without further discussion.

What we claim is:

1. In a buttonhole cutting machine, the combination with a fixed supporting frame, of a series of carriers slidably mounted thereon, cutting mechanism comprising an independent anvil and associated die mounted 95 on each carrier, said dies being set in arms pivotally secured to said carriers and disposed above said anvils, means for simultaneously shifting said carriers bodily along the frame so that each carrier is moved to 100 an extent proportional to its distance from the end of the series, a common actuating bar extending above said series of carriers and mechanically independent thereof, said bar adapted to engage said pivoted arms and 105 thus operate the dies, and means for reciprocating said bar.

2. In a buttonhole-cutting machine, the combination with a group of cutting devices, and a single additional cutting device disposed at the end of the group, means for simultaneously actuating all of said devices, mechanism for shifting the position of the members of said group, relative to each other, and independent mechanism for adjusting 115 the position of said single additional cutting device at the end relative to the first member of the group.

3. In a buttonhole cutting machine, the combination with a supporting frame, of a 120 series of independent cutting devices carried thereby, one of said devices being fixed to the frame, and the others being slidably mounted thereon, each of said devices comprising a body portion engaging the frame, 125 an anvil secured to said body portion, and a die-carrying arm pivotally mounted on said body portion, a lazy tong structure disposed underneath said series of cutting devices and secured at one end to the body 130

portion of said fixed cutting device, the body portions of the movable cutting devices having grooves in which the pivot pins of the intermediate joints of the lazy tong structure engage, means for simultaneously actuating said die-carrying arms, and means for operating said lazy tong structure to shift said movable cutting devices.

4. In a buttonhole-cutting machine, the combination with a supporting frame, of a plurality of cutting devices mounted thereon, each comprising an arm, a common actuator for said devices, and a resilient cushioning element interposed between said actuator and the arm of each cutting device.

5. In a buttonhole-cutting machine, the combination with a supporting frame, of a plurality of cutting devices mounted thereon, each comprising a pivoted arm and a rigid anvil, and means for applying a yielding pressure on said arms to actuate the same.

6. In a buttonhole cutting machine, the combination with a supporting frame, of a plurality of cutting devices mounted thereon, each comprising a pivoted arm, a common actuating bar independent of said cutting devices for simultaneously operating the pivoted arms thereof, and means movably mounted on each arm, serving, when in one position, to transmit movement of said actuator to said arm, and, when in another

position, preventing the operation of the arm by said actuator.

7. In a buttonhole cutting machine, a series of cutting devices each comprising a pivoted arm, and all of said arms being of substantially the same length, a blade mounted at the end of each arm, the blades of all of the cutting devices except the end one lying in parallel planes, the end blade being so connected with its arm as to permit adjustment at an angle to such planes, and means for varying the effective length of the arm carrying such angularly adjustable blade.

8. In a buttonhole-cutting machine, the combination with a series of cutters, of a work table disposed adjacent thereto, and a gage mounted on said table in position to be engaged by the work, said gage comprising a bar laterally adjustable on said table for determining the distance of the buttonholes from the edge of the garment, and a bracket adjustable on said bar for determining the distance of the last buttonhole from the end of the garment.

In testimony whereof we have affixed our signatures.

HARRY SILVERBERG.
CLARENCE W. BURGER.
